UNITED STATES PATENT OFFICE

WILLIAM C. McWHIRTER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRIC LOCK

Application filed January 8, 1930. Serial No. 419,289.

My invention relates to electric locks and particularly locks for preventing the unauthorized operation of railway traffic controlling devices such as switches, derails and the like.

One of the objects of my present invention is the provision of an electric lock operating independently of the manually operated actuating mechanism for the traffic governing device, and embodying various novel and improved features of construction and operation.

I will describe one form of electric lock embodying my invention which for the purpose of example, I have shown in connection with a railway track switch, and will then point out the novel features thereof in claims.

In the accompanying drawings, Fig. 1 is a top plan view showing the position of the electric switch lock relative to a track switch and the manually operated switch actuating mechanism. Fig. 2 is a top plan view of an electric lock constructed in accordance with my invention with the cover and terminal board removed. Fig. 3 is a view partly in side elevation and partly in vertical section taken on line III—III of Fig. 2. Fig. 4 is a vertical sectional view taken on line IV—IV of Fig. 3, with the electromagnets and latch mechanism shown in elevation. Fig. 5 is a vertical sectional view taken on line V—V of Fig. 4.

Similar reference characters refer to similar parts in each of the several views.

Referring to the drawings, and particularly to Fig. 1 thereof, an electric switch lock constructed in accordance with my invention and indicated in its entirety in Fig. 1, by the numeral 1, is shown as being mounted on a tie 2 adjacent the movable rails 3 of a track switch. The rails 3 are moved between normal and reverse positions with respect to the main rails 4 of the track by means of an operating rod 5 which is operatively connected with a switch operating mechanism 6, of any preferred type. This mechanism is also mounted on the ties 2 and is actuated by a manually operable lever 7. The switch is locked in its normal position by means of a lock rod 8 which is secured at one end to one

of the rails 3 and the other end of which extends into the electric lock 1 and is engaged thereby in a manner now to be described.

Referring now also to Figs. 2, 3, 4 and 5, the electric lock 1 is shown as comprising a casing formed with a lower portion 9 and an upper portion or cover 10 which is hinged to the lower portion, as at 11, and which may be locked in a closed position by a suitable fastening device 12. A housing 13 is secured to one of the side walls of the lower portion 9 of the casing and is formed with a guideway 14 in which the lock rod 8 is mounted for sliding movement. A horizontally extending rockshaft 15 is journaled at one end in a bearing 16 (Fig. 4) formed on a web or bracket 17 which is carried by a side wall of the lower portion 9 of the casing, and the other end thereof extends into the housing 13 and is journaled in a bearing 18 formed in the adjacent side wall. A foot operated lever 19 is fixed intermediate its ends to one end of the shaft 15, and one arm thereof extends through an opening 21 (Fig. 3) in the housing 13 and is formed with a pedal portion 22. The other arm 23 of the lever 19 is pivotally connected with the upper end of a locking dog 24 which is mounted for vertical sliding movement in a guideway 25 formed in the housing 13 for engagement with a notch or opening 26 formed in the switch lock rod 8. When the outer end of the lever 19 is depressed by the foot of the operator, to the position indicated by broken lines in Fig. 3, the inner arm 23 will swing upwardly and lift the locking dog 24 out of engagement with the lock rod 8.

A lever 27 is fixed to the shaft 15 within the casing and is provided with an upwardly extending latch arm 28 formed with opposed shoulders 29 (Fig. 5). These shoulders are adapted to engage opposite sides of a latch 30 which is carried by a vertically swinging arm 31 and which is maintained against lateral displacement by a slotted guide member 32 fixed to the adjacent side wall of the casing. The arm 31 is fixed to an armature 33 which is pivotally mounted on a bracket 34 provided with feet 35^a for engagement with lugs 35 formed on the side walls of the casing 9 (Fig. 4). This bracket also carries 100

a pair of electromagnets 36 which, when energized, as will presently be described, cause the armature 33 to swing the arm 31 and latch 30 upwardly and out of engagement with the shoulders 29, thereby permitting the shaft 15 to be rocked about its axis by depressing the pedal 22. A weight 31^a is mounted on the arm 31 for longitudinal adjustment and augments the weight of the 10 arm so as to insure that it will drop under the action of gravity and carry the latch 30 between the shoulders 29 when the magnets 36 are de-energized so as to lock the shaft 15 against rotation.

15 The energization of the magnets 36 is controlled by a contact device comprising a contact tip 38 and a cooperating spring contact finger 39 which are carried by a terminal board 37 which is also mounted on the 20 bracket 34. The finger 39 is moved into and out of engagement with the contact 38 by an arm 40 which is attached at one end to an insulating block 41 carried by the finger. The other end of the arm 40 is slotted for 25 engagement with a spool-shaped member 42 which is fixed to a lever 43. This lever is pivotally mounted at one end to a bracket 43^a secured to the under surface of the terminal board 37, and is formed at its other 30 end with a cam portion 44 for engagement with a cam surface 45 provided on an arcuate cam 46 carried by the latch arm 28. When the shaft 15 is rocked in a clockwise direction, as viewed in Fig. 5, the cam surface 45 35 of the arm 46 engages the cam portion 44 of the lever 43 and lifts this lever and the arm 40 sufficiently to carry the spring finger 39 into engagement with its contact 38, thus establishing a circuit through the windings 40 of the magnets 36 and causing the energization thereof.

The lever 27 is also formed with a depending bifurcated arm 47 which is pivotally connected with one end of a plunger 48. This 45 plunger extends through an opening 49 in a barrel 50 secured to the side wall of the casing, and through a bore 51 in the side wall. The plunger 48 is formed with a reduced central portion 52 forming a pair of spaced 50 shoulders 53 and 54 and carries a pair of slidable members preferably in the form of washers 55 and 56. A compression spring 57 surrounds the reduced portion 52 intermediate the washers 55 and 56 and, when 55 the parts occupy the positions shown in Fig. 5, tends to maintain the washer 55 in engagement with the shoulder 53 and the washer 56 in contact with the end of the barrel 50 which latter forms an abutment for limiting 60 the movement of the washer 56. It will be noted at this point that, when the parts occupy the positions shown in Fig. 5, the washer 55 is spaced a slight distance from the side wall of the casing, which also constitutes an 65 abutment for the washer 55, and the washer

56 is spaced a like distance from the shoulder 54 on the plunger 48. The purpose of this spacing will be described hereinafter. The spring 57 is maintained under compression in this position by a lever in the form of a cover 58 which is hinged to the exterior of the side wall as at 59 and is formed with a lug 60 for engagement with the end of the plunger 48. This cover is releasably secured in the position illustrated by a padlock 61 which may be inserted in an eye 62 for engagement with a hasp 63 provided on the cover. The plunger 48 is also formed with a circumferential groove 64 for engagement by a lip 65 formed on a detent 66. This 70 detent is mounted on the outer surface of the wall of the casing for vertical sliding movement and is maintained against displacement by a pin 67 which extends through an elongated aperture 68 formed in the upper portion of the detent. The detent is also formed with an aperture 69 through which the plunger 48 is adapted to project and with a projection 70 for engagement by a cam 71 formed on the cover 58. The detent is urged downwardly by means of a spring 72 which is mounted in a recess 73 formed in the detent and which bears upwardly against the pin 67.

The electromagnets 36 are connected in 95 series and are energized from any suitable source such as a local battery 76. Current from this battery traverses a circuit from one terminal thereof, through a contact device 77, windings of magnets 36, a terminal post 100 78 carried by terminal board 37, contact arm 39, contact tip 38, a terminal post 79 also carried by terminal board 37 and back to the other terminal of battery 76. The contact device 77 may be of any preferred type such, 105 for example, as the front contact of a track relay which is energized when the track section including the switch shown in Fig. 1 is unoccupied. With such an arrangement the contact device 77 is normally closed but 110 will open in the usual manner when a train enters the section and thereby prevent the energization of the magnets 36 and the operation of the lock mechanism.

Under certain conditions it is desirable 115 to visually indicate the condition of the lock and to this end I provide a contact device comprising a contact arm 80 which is preferably mounted on the armature 33 for engagement with a contact tip 81 connected with a terminal 82 carried by the terminal board 37. This contact device may be employed to control a suitable indication circuit, not shown but which is well known in the art. As shown 120 in the drawing, the contact device 80-81 is normally closed but will open when the magnets 36 are energized to operate the lock. It will be understood, however, that this contact may be arranged so that the necessary 125

indications may be obtained with a normally open circuit if so desired.

5 A contact tip 84 is also provided for engagement by the contact arm 39 when the magnets 36 are de-energized. This contact tip is connected with a terminal post 85 carried by the board 37, and may be employed for other purposes necessitating a normally closed circuit.

10 Considering the parts in the positions shown by full lines in the drawings, in which the switch rails 3 are locked in their normal position, the operation of my improved electric switch lock is as follows.

15 If it is desired to move the switch rails 3 to the reverse position, the trainman first removes the padlock 61 from the eye 62, thereby permitting the spring 57 to expand until the washer 55 engages the side wall of the 20 casing. This action of the spring 57 forces the rod 48 to the left as viewed in Fig. 5, and not only positively opens the cover 58 but rocks the lever 28 and shaft 15 in a clockwise direction sufficiently to carry the cam 25 surface 45 of the arm 46 beneath the lug 44 and elevate the lever 43. It will be noted from an inspection of Fig. 5 that there is sufficient play or lost motion between the shoulders 29 and the latch 30 to permit this 30 partial rocking movement of the parts. The upward swinging movement of the lever 43 elevates the arm 40 and moves the spring contact finger 39 into engagement with its contact tip 38, thereby completing an electric 35 circuit which energizes the electromagnets 36. The energization of these magnets attracts the armature 33, and swings the arm 31 upwardly and the latch 30 carried thereby 40 out of engagement with the shoulders 29 of the latch arm 28. The above described movements occur practically instantaneously following the release of the cover 58. The trainman then depresses the pedal 22, thereby 45 swinging the arm 23 of the lever 19 upwardly and lifting the dog 24 from locking engagement with the recess 26 in the switch lock rod 8.

The depression of the pedal 22 in the manner described also rocks the shaft 15 in a clockwise direction, as viewed in Fig. 5, and causes the arm 47 of the lever 27 to force the plunger 48 to the left against the action of the spring 57 through the engagement of the shoulder 54 with the washer 56. This 55 movement continues until the locking dog 24 is completely disengaged from the rod 8 at which time the groove 64 in the plunger 48 registers with the lip 65 of the detent 66 and is engaged thereby under the action of the spring 72. This locks the mechanism in an ineffective position and permits the trainman to actuate the track switch by means of the hand lever 7. As long as the parts 60 occupy these positions it is impossible for the

switch to be locked in either its normal or reverse positions.

When, however, the trainman desires to lock the switch in its normal position it is only necessary for him to swing the cover 58 back to its closed position and to reinsert the padlock 61 in the eye 62. The cover when thus moved functions as a lever and first carries the cam 71 into engagement with the under surface of the projection 70 on the detent 66 and lifts the detent until the lip 65 thereof is disengaged from the groove 64 in the plunger 48. As soon as plunger 48 is released by detent 66, spring 57 forces the plunger toward the right as viewed in Fig. 5, 75 and rocks the levers 27 and 19 in a counter-clockwise direction and reinserts the locking dog 24 in the notch 26 of the switch lock rod 8. The final portion of the motion of cover 58 to its closed position causes lug 60 to engage plunger 48, and returns the plunger to the position shown in the drawing thus insuring that cam surface 45 on the arm 46 is moved out of engagement with the lug 44 on the lever 43, and permitting the spring 80 contact finger 39 to move out of engagement with its contact tip 38. This breaks the circuit through the electromagnets 36 and causes the release of the armature 33. As soon as the armature is released the arm 31 drops and carries the latch 30 to its locking position between the shoulders 29 on the latch arm 28. This will prevent any subsequent movement of the pedal 22 except under the conditions 85 hereinbefore described.

90 In describing my invention I have assumed that the switch is locked in its normal position but it is apparent that by properly positioning the notches in lock rod 8, the device may be arranged to lock the switch in the reverse position, or, in either the normal or the reverse position.

95 Although I have herein shown and described only one form of electric lock embodying my invention, it is understood that various changes and modifications may be made therein within the scope of the appended claims without departing from the spirit and scope of my invention.

100 Having thus described my invention, what I claim is:

1. A locking device for railway traffic controlling apparatus comprising a locking dog, yieldable means for maintaining said dog in locking engagement with a member movable with said apparatus, manually operable means for moving said dog out of engagement with said member against the action of said yieldable means, a latch for controlling the operation of said manually operable means, electromagnetic means for actuating said latch to release said manually operable means, means actuated by said yieldable means for controlling the energization 110 of said electromagnetic means, and manually 115

operable means for rendering said yieldable means ineffective.

2. In combination, a rod movable by a railway traffic controlling apparatus, a dog for locking said rod against movement, yieldable means for maintaining said dog in locking engagement with said rod, manually operable means for moving said dog out of engagement with said rod against the action of said yieldable means, a latch for controlling the operation of said manually operable means, electromagnetic means for actuating said latch to release said manually operable means, means actuated by said yieldable means for controlling the energization of said electromagnetic means, and other manually operable means for rendering said first named manually operable means ineffective.

3. In combination, a rod movable with a railway traffic controlling apparatus, a locking dog for locking said rod against movement, yieldable means for maintaining said dog in locking engagement with said rod, manually operable means for moving said dog out of engagement with said rod against the action of said yieldable means, a latch for controlling the operation of said manually operable means, electromagnetic means for actuating said latch to release said manually operable means, means actuated by said yieldable means for controlling the energization of said electromagnetic means, and other manually operable means for rendering said yieldable means and said first mentioned manually operable means ineffective.

4. In combination, a rod movable with a railway traffic controlling apparatus, a locking dog adapted to engage said rod, manually operable means for moving said dog out of engagement with said rod, a latch for controlling the operation of said manually operable means, electromagnetic means for actuating said latch to release said manually operable means, a contact device for controlling the energization of said electromagnetic means, a spring for actuating said contact device, and manually operable means for releasably maintaining said locking dog in engagement with said rod independently of said latch and for rendering said spring ineffective.

5. In combination, a rod movable with a railway traffic controlling apparatus, a locking dog mounted for engagement with said rod, a lever for moving said dog out of engagement with said rod, electromagnetic means for controlling the operation of said lever, a contact device for controlling the operation of said electromagnetic means, a spring for yieldably maintaining said dog in engagement with said rod and for operating said contact device, and manually operable means for controlling the operation of said lever and for rendering said yieldable means ineffective.

6. In combination, a rod movable with a railway traffic controlling apparatus, a locking dog, a lever for moving said dog to an ineffective position, a latch for controlling the operation of said lever, electromagnetic means for actuating said latch to release said lever, a contact device for controlling the energization of said electromagnetic means, yieldable means operable in two directions for urging said dog toward its effective position and for closing said contact device, and manually operable means for releasably maintaining said yieldable means ineffective with respect to said contact device.

7. A locking device for railway traffic controlling apparatus comprising means mounted for locking engagement with a member movable with said apparatus, yieldable means for maintaining said locking means in its locking position, manually operable means for moving said locking means toward an unlocked position, latch mechanism for controlling the operation of said manually operable means, electromagnetic means for controlling the operation of said latch mechanism, a contact device operated by said yieldable means for controlling the operation of said electromagnetic means, and other manually operable means for controlling the operation of said contact device by said yieldable means and for controlling the operation of said first manually operable means jointly with said latch mechanism.

8. A locking device for railway traffic controlling apparatus comprising means mounted for locking engagement with a member movable with said apparatus, a spring for yieldably maintaining said locking means in its locking position, a pedal for moving said locking means toward an unlocked position, latch mechanism for controlling the operation of said pedal, electromagnetic means for controlling the operation of said latch mechanism, a contact device operated by said spring for controlling the operation of said electromagnetic means, and a manually operable lever for controlling the operation of said contact device by said spring and for controlling the operation of said pedal jointly with said latch mechanism.

9. A locking device for railway traffic controlling apparatus comprising a dog mounted for locking engagement with a member movable with said apparatus, a pedal for moving said dog to an unlocked position, a latch for controlling the operation of said pedal, electromagnetic means for controlling the operation of said latch, a contact device for controlling the operation of said electromagnetic means, cam mechanism for operating said contact device, a spring operable in one direction to oppose the operation of said pedal and in an opposite direction to actuate said cam, and a manually operable device for controlling the opera-

tion of said cam mechanism by said spring and the operation of said pedal jointly with said latch.

10. A locking device for railway traffic controlling apparatus comprising a dog mounted for locking engagement with a member movable with said apparatus, a pedal for moving said dog to an unlocked position, a latch for controlling the operation of said pedal, electromagnetic means for controlling the operation of said latch, a contact device for controlling the operation of said electromagnetic means, cam mechanism for operating said contact device, a plunger for operating said cam mechanism and having an operative connection with said pedal, said plunger having a pair of spaced opposed shoulders, a pair of spaced fixed abutments one adjacent each of said shoulders, members slidably mounted on said plunger for engagement with said shoulders and said abutments, a spring surrounding said plunger between said members, and manually operable means for releasably retaining said spring under compression between said members with one of said members in engagement with its adjacent shoulder and spaced from the adjacent abutment and the other of said members in engagement with its adjacent abutment and spaced from its adjacent shoulder; whereby when said retaining means is released said spring will actuate said plunger to operate said cam mechanism and thereafter yieldably oppose the operation of said pedal.

11. A locking device for railway traffic controlling apparatus comprising a dog mounted for locking engagement with a switch lock rod, a pedal for moving said dog to an unlocked position, a latch for controlling the operation of said pedal, electromagnetic means for controlling the operation of said latch, a contact device for controlling the operation of said electromagnetic means, cam mechanism for operating said contact device, a plunger for operating said cam mechanism and having an operative connection with said pedal, said plunger having a pair of spaced opposed shoulders, a pair of spaced fixed abutments one adjacent each of said shoulders, members slidably mounted on said plunger for engagement with said shoulders and said abutments, a spring surrounding said plunger between said members, manually operable means for releasably retaining said spring under compression between said members with one of said members in engagement with the adjacent shoulders and spaced from the adjacent abutment and the other of said members in engagement with its adjacent abutment and spaced from its adjacent shoulder; said retaining means when released permitting said spring to actuate said plunger to operate said cam mechanism and thereafter yieldably oppose the operation of

said pedal, and a detent for releasably engaging said plunger to maintain said pedal in the position to which it was moved against the action of said spring when actuated to disengage said dog from said switch lock rod.

12. A locking device for railway traffic controlling apparatus comprising a dog mounted for locking engagement with a switch lock rod, a pedal for moving said dog to an unlocked position, a latch for controlling the operation of said pedal, electromagnetic means for controlling the operation of said latch, a contact device for controlling the operation of said electromagnetic means, cam mechanism for operating said contact device, a plunger for operating said cam mechanism and having an operative connection with said pedal, said plunger having a pair of spaced opposed shoulders, a pair of spaced fixed abutments one adjacent each of said shoulders, members slidably mounted on said plunger for engagement with said shoulders and said abutments, a spring surrounding said plunger between said members, manually operable means for releasably retaining said spring under compression between said members with one of said members in engagement with the adjacent shoulders and spaced from the adjacent abutment and the other of said members in engagement with its adjacent abutment and spaced from its adjacent shoulder; said retaining means when released permitting said spring to actuate said plunger to operate said cam mechanism and thereafter yieldably oppose the operation of said pedal, a detent for releasably engaging said plunger to maintain said pedal in the position to which it is moved against the action of said spring, and means carried by said manually operable means for disengaging said detent from said plunger when said manually operable means is returned to its retaining position.

13. A locking device for railway traffic controlling apparatus comprising a dog mounted for locking engagement with a member movable with said apparatus, a pedal for moving said dog to an unlocked position, a latch for controlling the operation of said pedal, electromagnetic means for controlling the operation of said latch, a contact device for controlling the operation of said electromagnetic means, cam mechanism for operating said contact device, a spring operable in one direction to oppose the operation of said pedal and in an opposite direction to actuate said cam, a manually operable device for controlling the operation of said cam mechanism by said spring and the operation of said pedal, and second contact device operated by said electromagnetic means for indicating the condition of said locking device.

14. A locking device for railway traffic controlling apparatus comprising a dog

mounted for locking engagement with a member movable with said apparatus, a pedal for moving said dog to an unlocked position, a latch for controlling the operation of said pedal, electromagnetic means for controlling the operation of said latch, a double acting contact device for controlling a plurality of electric circuits, one of said circuits controlling the operation of said electromagnetic means, cam mechanism for operating said contact device, a spring operable in one direction to oppose the operation of said pedal and in an opposite direction to actuate said cam, and a manually operable device for controlling the operation of said cam mechanism by said spring and the operation of said pedal.

In testimony whereof I affix my signature.
